ARTICULATION JOINT FOR LOCOMOTIVES
AND CARS

Leo J. Seider, Philadelphia, Pa., assignor to The Pennsylvania Railroad Company, Philadelphia, Pa., a corporation of Pennsylvania

Application June 1, 1937, Serial No. 145,692

2 Claims. (Cl. 105—175)

This invention relates to the load coupling articulation of locomotive or railroad car trucks to the underframe structure of such vehicles, while it has more particular reference to a novel form of disassemblable articulation adapted for electric locomotives.

Heretofore articulation means of the type above referred to have possessed one very objectionable feature, namely that when renewal or repair of the coupling connection became necessary, the respective frame units have had to be relatively separated and the superstructure firstly removed. This procedure is not only costly, but involves considerable work, and it is the primary aim of the present invention to provide an articulation arrangement for locomotives and cars by the adoption of which the recited disadvantages are effectively overcome.

Another object is to furnish an articulation arrangement of the indicated character which can be expeditiously disassembled, and renewal of worn or damaged parts effected, without disturbing or removing the locomotive cab or car body from its supporting substructure.

Still further, this invention has for an object the provision of an articulation arrangement for locomotives and railroad cars which is at all times as dependable as it is highly efficient in use, and wherein the articulative functions are satisfactory at all times.

With the above recited and other objects in view, this invention comprises certain novel structural features, arrangements and combinations of parts, whereby the objects contemplated are attained; all as hereinafter more fully set forth, particularly defined in the claims, and shown by the accompanying sheets of illustrative drawings.

In said drawings:

Fig. I is a side elevation of an electric locomotive having an articulation arrangement in accordance with this invention.

Fig. II is a plan view of the articulation joint assembly broken out from the locomotive or car substructure.

Fig. III is a vertical section on the plane designated III—III in Fig. II, and drawn to a larger scale.

Fig. IV is a vertical section on the plane IV—IV of Fig. III.

Fig. V is a vertical section through the articulation means with the pivot ball and bearing elements thereof removed.

Fig. VI is a detail perspective view of the pivot ball-block components in expanded relation.

Fig. VII is a detail perspective view of a pivot or articulation ball.

Fig. VIII is an inverted perspective view of a lower bearing member forming a part of the improved articulation arrangement; and,

Fig. IX is a detail perspective view of a split ring, hereinafter fully explained.

Referring in greater detail to the drawings, and more particularly to Fig. I, an electric locomotive of known type is comprehensively designated by the reference 10, the same being mounted on two frame units 11, 12, which are conventionally connected, midway of the length of said locomotive, by the coupling means 13 of this invention, that is referred to hereinafter as an articulation-joint. As best understood from Figs. II—V, the one frame unit 11 has its inner ends integrally united by a transverse connection 14 embodying upper and lower apertured arms 15, 16, respectively, the former of which is fitted with an appropriate liner 17. The aperture 18 of the lower arm 16 is of much larger diameter than aperture 19 of the upper arm 15, for a purpose hereinafter set forth, and is fitted with a removable bushing 20 and liner 20', held in place by bolts 21. The bushing has downwardly extending lugs 22, having openings 22' therethrough for reception of a transverse bolt 23, the purpose of which is later on explained.

The other frame unit 12 is formed with an apertured coupler extension 24 in which are housed a pair of opposing semi-spherically cupped-blocks 25, 26 embodying annular centering projections 27, 28, affording shoulders 29, 30, and jointly providing a substantially spherical seat for a ball member 31. The cupped blocks 25, 26 are supported and secured in place, with capacity for easy dismantling by means of a peripherally flanged split ring 32 and clamp bolts 33, as clearly understandable from Fig. IV. The member 31, as best understood from Fig. VII, is somewhat in the nature of an axially orificed ball, through the bore 34 of which the coupling pin 35 passes, said pin having a head 36 at its lower end for abutment against the confronting annular face of the bushing 20, and it is held in place against downward longitudinal movement by the transverse bolt 23, aforesaid, in an obvious manner.

Referring again to the liners 17 and 20', it is to be noted their upper ends are peripherally flanged at 37, 37', respectively, for socketing support in counterbores of the upper arm aperture 19, and the top portion of the bushing 20.

For the purpose of lubricating the articulation

joint 13, the pin 35 is provided at its upper end with an axial bore 38 having a central outlet 39 with radial branches 40 opening out at a slight elevation relative to the top of the ball member 31; while the latter is provided with upper and lower circumferential grooves 41, 42, as well as one or more downwardly directed arcual grooves 43 from its top to the first mentioned groove 41. These provisions afford ample flow communication for lubricant contained in the bore 38 downwardly to all of the movable parts of the articulation joint 13, in an obvious manner; while said bore is provided with a suitable filling closure or cap 44. 45 designates a screw-threaded axial bore in the head of the coupling pin 35 for application of a suitable implement or tool for removing said pin as hereinafter explained.

From the foregoing, the operation of the improved articulation joint 13 will be self-evident, while it will be readily understood that when disassembling of said joint becomes necessary in order to renew or readjust the ball member 31, or the bearing blocks 25, 26, the transverse bolt 23 is first removed and the coupling pin 35 dropped-out or withdrawn by application of a suitable implement to the threaded bore 45. The bushing 20 and associated liner 20' is next allowed to drop out by removing the nuts from the lower ends of the bolts 21, whereupon an ample opening (the bore 18 of the arm 16) is provided for access to the nuts of the clamp bolts 33 and removal of the split ring 32. The ball member 31 with its associated blocks 25, 26 can now be easily removed or dropped through the bore 18 aforesaid, and the necessary replacement or repairs effected, without in any way disturbing the locomotive frame units 11, 12, or the cab C, Fig. I, of said locomotive.

Obviously structural variations may be made in the foregoing disclosure without departing from the scope of the invention as set forth, it is therefore intended that all matters contained in the description or shown by the accompanying drawings shall be interpreted as illustrative and not in a limiting sense.

Having thus described the invention, I claim:

1. In articulation joints for locomotive and railroad car frame units including interregisterable end projections, means for coupling said units together comprising an axially-orificed ball member and bearing case blocks removably supported by a peripherally-flanged split ring secured to the end projection of one frame unit, spaced circumferential grooves in the ball member with intervening arcual grooves for lubricant distribution, a sleeve sustained by the end projection of the other frame unit, a pivot pin passing through said sleeve and ball member, means included in the sleeve structure directly supporting the pivot pin against axial displacement, and said sleeve being of an external diameter such that, when the pivot pin and the sleeve are withdrawn and the split ring removed, the ball member and bearing case blocks may be released and downwardly withdrawn, or replaced, through the aperture afforded by the removal of said sleeve and split ring without disturbing the locomotive or car superstructure.

2. An articulation joint as defined in claim 1, wherein the upper end of the pivot pin is provided with an axial lubricant-storage bore having a central outlet with radial branches communicating into one of the ball-bearing circumferential grooves.

LEO J. SEIDER.
